UNITED STATES PATENT OFFICE.

WILLIAM C. BAXTER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

CUTTING-MACHINE.

1,291,726.

Specification of Letters Patent. Patented Jan. 21, 1919.

Application filed March 11, 1915. Serial No. 13,873.

To all whom it may concern:

Be it known that I, WILLIAM C. BAXTER, a citizen of the United States, residing at Beverly, in the county of Suffolk and State 5 of Massachusetts, have invented certain Improvements in Cutting-Machines, of which the following description, in connection with the accompanying drawings, is a specification, like reference characters on the drawings indicating like parts in the several 10 figures.

This invention relates to cutting machines and is herein shown as embodied in a machine, of the type known to the trade as 15 "dinking machine". It will be understood, however, that the invention is not restricted either to machines of the illustrated type or to the illustrated constructional details.

The machine herein shown is intended for 20 use in cutting blanks from sheet material moved by successive feeding operations into position between the elements of the cutting mechanism, the illustrated cutting mechanism being adapted to cut heel lifts. Besides being formed from leather, heel lifts 25 are now formed from various other materials, such as leatherboard, vulcanized fiber, and so-called "pancake" stock, and in cutting lifts from some of these materials it is 30 frequently advantageous to separate the material from which the lifts are immediately to be died from the sheet as the cutting operation proceeds, thus avoiding the cutting into strips of more material than may be 35 needed to make the required number of heel lifts of a given size. It is also a common practice to cut the material into strips before it is presented to the cutting machine, this being, of course, necessary when cutting 40 wedge lifts.

One of the objects of the present invention is to provide a cutting machine of general utility in the dinking field, and particularly to provide an improved cutting machine 45 which can be readily adapted for use either upon strips which have been cut in a separate machine, or upon material in the sheet form.

In the feeding of the material to be cut 50 in dinking machines difficulty has been experienced in the past in obtaining a positively

uniform feed, and also in so feeding the material that there would be no waste at the two ends. Further important objects of the invention, therefore, are to provide improved 55 feeding mechanism which will feed the material with great precision and uniformity, to provide feeding mechanism which will insure the positioning of the leading end of the material so that the first blank may be 60 cut without substantial waste, to provide means to insure the positioning of the last end of the material so that no piece of material of a size to furnish a complete blank will be discarded, to provide improved 65 means for controlling the presentation of the material to the cutting mechanism, and to provide convenient and certain adjustments whereby the various mechanisms may be quickly and easily adapted to the production 70 of blanks of different sizes.

It is important in cutting blanks from a strip, or in cutting blanks from a sheet and separating from the sheet the portion of material from which the blanks are cut, that the 75 width of the portion from which the blank is cut be as carefully measured and located with respect to the die as the length, using the term "width" in this expression to designate that dimension of the blank which is 80 transverse to the direction of feed, and the term "length" to designate the dimension which coincides with the direction of feed. To this end the invention aims further to provide improved locating means so that the 85 material from which the blank is cut may be cut to a width approximately equal to the width of the blank, thus avoiding waste in this dimension.

A very important object of the invention 90 is to provide a machine which can be operated at high speed, and to this end the invention aims to provide cutting mechanism which is both light and strong. An important feature of this cutting mechanism is a 95 novel cutting block which insures a clean uniform cut and scarcely ever requires resurfacing.

An important feature of the cutting mechanism is the provision of means for securing 100 a very accurate location of the block and cutter with respect to each other in all

dimensions. In the illustrated preferred construction of the invention the cutting block comprises a metal plate having a definite location upon the cutting block support, and in this metal plate is formed a die receiving groove having the exact outline of the cutting edge of the die, this groove being preferably formed after the block and die have both been located in certain definite locations in the machine to which they can always be returned when they are removed for replacement by coöperating blocks and dies of other sizes.

A further important feature of the invention is the provision for a fine positive adjustment of the limit of approach of the die and block whereby the cutting edge of the die may be caused to enter to a predetermined depth into the groove in the block.

Other important features and objects of the invention will appear from the following description and claims, when considered in connection with the accompanying drawings, in which,—

Figure 1 is a perspective view of a machine embodying the invention, the work table, waste chute and one of the supporting brackets for the work table being broken away to disclose parts of the machine otherwise concealed;

Fig. 2 is a view, partly in section, of the work feeding and controlling mechanism;

Fig. 3 is a view similar to Fig. 2 but showing the table removed and the parts of the feeding mechanism in a different position, and also showing the stock about to be cut;

Fig. 4 is a perspective detail showing the arrangement of, and the supports for, the front and rear gages and the stripper mechanism, the gage slide being drawn back;

Fig. 5 is a perspective view of the feeding mechanism and the means for operating it;

Fig. 6 is a sectional view through the feed operating mechanism;

Fig. 7 is a sectional detail illustrating the arrangement of the feed wheel supporting shafts whereby the feed wheels accommodate themselves automatically to variations in the thickness of the stock;

Fig. 8 is a view of the means for adjusting the feed operating mechanism;

Fig. 9 is a detail view, partly in section, of the roller ratchet which constitutes an element of the feed operating mechanism;

Fig. 10 is a vertical section through the front part of the head of the machine, illustrating particularly the construction of the plunger, block carrier, die, die holder, and the location of the gages with respect to the die;

Fig. 11 is a detail section illustrating the cutting operation;

Fig. 12 is a detail perspective showing the mode of operation of the gate by which the feed of the leading end of the stock is controlled;

Fig. 13 is a sectional view illustrating the arrangement of the bearings for the feed wheel shafts and of the toggle which connects the shafts;

Fig. 14 is a detail perspective showing the eccentric means for operating the sifting chute;

Fig. 15 is a plan view of the die and die holder, this view illustrating the manner of mounting a die having a straight breast edge; and

Fig. 16 is a view similar to Fig. 15 showing the manner of mounting a die having a curved breast edge.

The operating parts of the machine are carried by a head 2 supported upon a stand 4, the head 2 being provided with front and rear bearings 6 and 8, respectively, for a shaft 10 which has formed at its front end an eccentric portion 12 serving as a crank pin to reciprocate a pitman 14 connected to a plunger 16 which carries at its lower end a support 18 for a cutting block 20. The cutting block 20 is reciprocated by the mechanism just described into and out of coöperative cutting relation to the upper edge of a die 22 carried upon a die support 24. The die 22 is open at both ends, and the material to be cut by the die passes through an opening below the die into a chute 26 upon the under side of the machine, which chute is provided with a sifting bottom formed of woven wire 28, whereby waste pieces, such as incomplete lifts, may be separated from the perfect lifts. The plunger 16 reciprocates in a bearing 30 at the front of the machine, and to prevent the cutting block from turning, the block support 18 is provided with a vertical guide rod 32 guided in a bearing 34 clamped to the side of the bearing 30.

The material to be operated upon is fed to the cutting mechanism by feeding means, shown particularly in Figs 2 to 7 of the drawings, the illustrated feeding means comprising toothed feed wheels 36 and 38 fastened upon shafts 40 and 42 which are provided at their rear ends with gears 44 and 46 which mesh respectively with pinions 48 and 50, the pinion 50 being driven from the pinion 48, and the pinion 48 being driven from a gear 52.

To provide for relative movements of approach and separation of the feed wheels 36 and 38, in order to accommodate stock of varying thicknesses without disturbing the connection between the gears 44, 46 and the pinions 48, 50, the feed wheel shafts 40 and 42 are mounted in bearings or supports 54 and 56, respectively, arranged to swing about the axes about

which the pinions 48 and 50 turn, the bearings or supports 54 and 56 being provided with arms 58 and 60 which are provided with hubs or sleeves 62 and 64 received upon stationary shafts 66 and 68 upon which the pinions 48 and 50 turn, there being one of the arms 58 and one of the arms 60 upon each side of a support 70 for the shafts 66 and 68. One of the swinging shaft supports 54 has a reduced portion 71 upon which the other support 54 is received together with one member 72 of a toggle connecting the shafts 40 and 42, the other member 74 of said toggle being received upon a reduced portion 73 of one of the supports 56. The two members of the toggle are connected together by a pivot pin 76.

The feed wheels 36 and 38 are normally kept at their adjusted limit of approach, 20 and provision is made for permitting them to separate yieldingly in order to accommodate different thicknesses of stock or variations in the thickness of the material being acted upon. To insure maintaining 25 the feed wheels yieldingly at their limit of approach a rod 78 is pivotally connected to the knee joint 76 of the toggles 72, 74, this rod being surrounded by a spring 80 which bears at one end against a bearing lug 81 upon the support 70 and at its other end against a washer 82 confined upon the rod 78 by nuts 84. To provide for adjusting the 30 limit of approach of the feed wheels the rod 78 has a threaded portion between its ends, 35 and upon this threaded portion is received a nut 86 located between the support 70 and the bearing lug 81, the spring 80 tending to draw this nut up against the bearing lug 81 as shown in Fig. 7, and the nut 86 being of 40 such dimensions that there is room for movement of the nut with the rod 78 as the feed wheels are separated.

The gear 52 which drives the pinions 48 and 50, and through them the gears 44 and 46 upon the feed wheel shafts, is intermittently turned in one direction through connections to the driving shaft comprising a roller ratchet, a link 90 and a gear 92 which carries a crank pin by which the link or pitman 90 is reciprocated, the gear 92 being driven by a gear 94 upon the driving shaft 10. The roller ratchet comprises a roller cage 96 received upon the hub 98 of the gear wheel 52, this cage being surrounded by a clutch ring 55 or casing 100 provided with an ear 102 to which the link 90, by which the ring or casing is oscillated, is pivotally connected. The inner surface of the ring or casing 100 is concentric with the axis about which it turns and the rollers 104, of which six are shown in the drawings, are confined in pockets 106 in the cage 96, these pockets or recesses having bottoms 108 eccentric to the inner surface of the ring or casing 100, so

that when the ring or casing 100 is turned 65 in one direction the rollers will lock the cage 96 to the ring or casing 100, whereupon the cage 96 is turned with said ring or casing. When the ring or casing 100 is turned in the reverse direction the rollers move toward 70 the larger end of the pockets, and the casing 100 moves over the cage 96 without turning.

A spring pressed plunger 110 entering each of the pockets 106 tends to move the roller 104 toward locking position in the 75 pocket. Connected to the roller cage 96 is a plate 112 which forms one member of a safety connection between the gear 52 and the roller ratchet. Located partly in the recess in the face of the part 112 and partly 80 in the opposed face of the gear 52 are balls 114 which operate to lock the gear 52 to the plate 112 so that said gear is turned with the cage 96 when the roller ratchet is moved in the operative direction, provision being 85 made for slippage of the gear 52 over the plate 112 in case of interference with the feeding operation. The hub 98 of the gear 52 is mounted upon a shaft 116 which is arranged to move lengthwise in a bearing 118 90 against the tension of a spring 120 to permit the balls 114 to move out of locking relation to the gear 52 and the plate 112 when the operation of the feeding mechanism is prevented for any cause. The spring 120 also 95 causes friction between the roller ratchet and the bearing 118 sufficient to prevent it from turning backward. The crank pin or wrist pin 122, upon the gear 92, by which the link or pitman 90 is reciprocated, is carried upon 100 a sliding block 124 mounted in a guideway 126 extending along the radius of said gear, and threaded into this block is an adjusting screw 128 so mounted in the gear as to be 105 held against endwise movement and provided in one end with a slot 130 to receive a screw driver for adjusting the wrist pin or crank pin 122 to vary the throw of the pitman 90, and thereby the amount of turning of the gear 52, when it is desired to vary 110 the amount of feed movement imparted to the feeding mechanism of the machine.

In order that the operator may conveniently adjust the length of feed to the size of the die an indicator 132 is mounted upon 115 the gear 92, this indicator co-operating with a scale 134 and being turned by the engagement of the screw 128 with a worm gear 136 connected to said indicator. The scale 134 may be graduated in any suitable manner, as for example in die sizes, so that the operator may immediately set the feeding mechanism to give the proper feed of the stock when he places a die of a certain size in the machine.

It will be noted that the feed wheels 36, 38 are located a short distance away from the edge of the die over which the stock is to be

fed, this location of the feed wheels being necessary in order that they may be out of the way of the cutting block. The normal feed movement imparted to the feed wheels is preferably just sufficient to feed the stock far enough so that a complete lift may be cut from it. To prevent waste it is necessary, therefore, in feeding the stock into position to cut the first lift, to feed it only far enough so that the leading end will just pass the further edge of the die, and to do this provision must be made for feeding this end of the stock through the distance which separates the feed wheels from the inner edge of the die. To this end, as in the machine shown in United States Letters Patent No. 1,113,699, R. C. Simmons, granted October 13, 1914, means is provided for preventing the introduction of the stock into the feed mechanism until the feed mechanism is in such position that, during its first feed movement or that part of it which is operative, it will feed the end of the stock to the inner edge of the die so that during the succeeding feed movement the stock will be fed into position to cut the first lift without wasting material at the end of the stock. The illustrated means comprises a gate 138 which is provided with a shoulder 140 presenting a front face substantially perpendicular to the plane of the stock and serving as a stop for the forward end of the stock, said gate member 138 being also provided with a foot 142 which extends through a slot in the feed wheel 36 and aids in guiding and controlling the stock as it is being fed. The gate 138 is intermittently lifted during the operation of the machine, and the illustrated means for lifting the gate comprise a link 144 pivotally connected at its lower end to a lug 146 upon said gate and pivotally connected at its upper end to an arm 148 upon a rock shaft 150 upon the side of the machine head, said rock shaft being provided with another arm 152 carrying a roll 154 bearing against an edge cam 156, a spring 158, coiled about said rock shaft and connected to a pin 160 upon said rock shaft and at its other end hooked over the bearing lug 162 for said shaft, tending to move the gate down into operative position and at the same time hold the roll 154 against the cam 156. It will thus be seen that the gate is yieldingly depressed into operative position but is positively raised. The gate is guided in a guideway 164, and the lug 146 projects through a slot in the front wall of said guideway. Coöoperating with the foot 142 upon said gate in guiding and controlling the stock is a spring member 166 which is received at its forward end in a notch 168 in a stripper member 170, the spring member being so shaped and arranged that it tends to rise above the notch 168 which is of such dimen-

sions that when said member is in said notch the upper surface is substantially flush with the upper surface of the stripper member. Thus when the stock is being introduced into the machine the spring member 166 tends to lift its forward edge both above the stripper member 170 and above the edge of the die. The spring member 166 extends beneath the stock supporting table 172 and at its end remote from the feeding mechanism is connected to a member 174 pivotally mounted upon the under side of said table 172, a coiled spring 176, surrounding a stud 178 upon the under side of said table, tending to press said member 166 up against the under side of said table with a pressure which varies with the adjustment of a nut 180 threaded upon said stud 178.

In order that the last end of the stock may be brought into such position that a lift may be cut therefrom when the piece left is large enough to make a complete lift, means is provided for pushing this piece over the die 22 as said piece is released by the feed wheels. The illustrated means comprises a pair of pusher fingers 182 which normally bear upon the under side of the stock but do not in any way coöperate in the normal feeding operations of the machine. These fingers are moved to and fro toward and away from the die 22 and in their extreme position away from the die have their forward ends so located that they may engage the rear end of the last piece of stock to be fed over the die as this end is released by the feed wheels 36 and 38. These fingers are received in slots 184 in the feed wheels, the slots in the lower feed wheel being deep enough so that when stock is passing between the feed wheels the fingers may be depressed into the slots against the tension of the spring 186 connected to an arm 188 located upon the side of the pivot 190 of said fingers remote from said fingers. The fingers 182 are pivoted at 190 upon an oscillating support 192 fulcrumed at 194 upon a bracket 196 upon the side of the die support, said support 192 being oscillated to move the fingers toward and away from the die 22 by connections to the main driving shaft. The operating connections for the fingers comprise a link 198 pivotally connected at its respective ends to said support 192 and to an arm 200 upon a rock shaft 202 which extends to the rear of the machine and is there provided with a second arm 204 connected by a link 206 with an arm 208 upon another rock shaft 210 upon the side of the machine head remote from that upon which the rock shaft 202 is located, said rock shaft 210 being provided with a second arm 212 carrying a roll 214 bearing against the edge of an eccentric or cam 216 which is attached to the shaft 218 upon which the gear 92 is mounted and

to which it is connected, the gear 92 being driven by the main shaft 10 in the manner hereinabove described. A spring 220 connected at one end to the arm 208 and at its other end to the machine frame tends to hold the roll 214 in engagement with the cam or eccentric 216 and to move the fingers 182 in the direction to feed the stock. The eccentric 216 thus operates to move the fingers 182 positively in the direction of the return movement of the fingers.

The material to be cut is guided to the feeding and cutting mechanisms by an edge guide 222 upon the table 172, said edge guide having an overhanging flange 224 near its forward end which serves to guide the leading end of the material as it is being presented to the machine. To insure the positioning of the leading end of the material against the shoulder 140 of the gate 138 an adjustable guard 226 for the upper feed roll is provided, said guard being carried upon a slide 228 adjustably held upon the front of the guideway 164 for the gate 138 by a set screw 230. The edge of the material is guided as it is fed into position over the die by an edge guide or gage 232 adjustably mounted upon a slide 234 which is arranged to slide transversely through a carrier 236 yieldingly held against vertical movement, whereby it may be moved downwardly by the cutting block 20 as said block forces the stock down into the die. The means for yieldingly supporting the carrier 236 comprises shouldered bolts 238 arranged to slide in vertical guides 240 in which springs 242 are confined between the bottoms of said guides and the shoulders on said bolts. From an inspection of Figs. 4 and 10 it will be seen that the inner faces of the die are substantially in vertical planes and that the inner cross sections are substantially uniform so that the lifts or other blanks cut may be easily forced down through the die, and, therefore, the cutting edge of the die must be formed by beveling the outer faces of the die to this edge. To provide for the location of the stock by the edge gage 232 so close to the cutting edge of the die that there will be substantially no waste in cutting said stock and at the same time to provide for the movement of this gage downward during the cutting operation, means is shown for causing the gage to move laterally as it is moved downwardly.

The illustrated means comprises a link 244 pivoted between ears upon the rear end of the slide 234 and between ears upon the forward end of an adjusting bolt 246 by which the position of the gage 232 with respect to the die can be adjusted. A hand nut 248, threaded upon said bolt 246 and confined between the rear face of the machine head and a bracket 250 bolted upon said head, is used for adjusting the gage. The slide

234, link 244 and bolt 246 are in substantially the same horizontal plane when the carrier 236 is at the upper limit of its movement, and therefore, as the gage 232 is forced downwardly by the cutting block 20, 70 the swinging of the link 244 about its pivot on the bolt 246 will draw the slide 234 back sufficiently to permit the gage 232 to pass over the inclined outer face of the die. The stripper member 170 is also mounted upon the carrier 236 and is moved downwardly as the material to be cut is forced down upon the die by the cutting block 20.

To provide for adjustment of the stripper member 170 toward and away from the die, 80 the bracket 252 in which the guides 240 are formed is confined upon the front of the head 2 with provision for lateral adjustment, said bracket being provided with a dovetailed guideway 254 which receives the squared head 256 of a bolt 258 extending through the head and having upon its rear end a nut 260 which presses a washer 262 against the rear face of the head 2 and draws the bracket up against the front face of the 90 head. Rabbets 264 upon either side of the guideway or groove for the bolt 258 are received in a horizontal groove in the front face of the head 2 and serve to guide the bracket 252 in its lateral movements of adjustment. A plate 266 (Fig. 1) fastened upon the left hand end of the bracket 252 carries a screw 268 bearing against a side of the head 2, said screw serving as a stop to determine the location of the bracket 252 100 when it has been adjusted, and also to effect such adjustment. A lock nut 270 holds the screw 268 in the desired position of adjustment.

The machine herein shown is designed to 105 be used either for operating upon stock in sheets or for operating upon strips. When operating upon strips which have been cut or formed outside the machine, another guide 272 is provided upon the table 172. 110 When operating upon sheet stock the guide 272 is removed, and means is provided for separating the material which is to be operated upon by the die from the remainder of the sheet as the material is being fed to the 115 die cutting mechanism.

The illustrated means for stripping the stock as it is being fed to the die comprises corrugated cutting disks 274 and 276 upon the respective shafts 40 and 42, these disks overlapping, the upper disk being of a diameter greater than the diameter of the feed roll 36, and the lower disk being of substantially the diameter of the feed roll 38. This arrangement of the disks permits the die, which is on the same side of the plane of the material as the lower feed roll, to be positioned close to the rolls without interference with the disk cutters. The cutting action of these disks is that of shears. The 120 125 130

corrugations are provided upon the disks to prevent the disks, as they engage the stock somewhat in advance of the engagement by the periphery of the feed rolls, from retarding the feeding action of the feed rolls by tending to force the stock back against said feeding action. It will be noted that a spacing member 278 is provided upon each of the shafts between the cutting disks 274, 276 10 and the end nuts 280 which confine the cutting disks 274, 276 and the feed rolls 36, 38 upon the shafts, the purpose of these spacing members being to permit the lengthening of the feed rolls when it is desired to use 15 the machine with a die which will cut two blanks at once, or when, for any reason, it is desired to cut from the sheet a wider strip.

To support the sheet as it is being presented to the feeding and stripping mechanism, a table 282 is provided in front of the table 172, this table being supported upon brackets 284 and 286 upon the front of the machine frame. To guide the front edge of the material to be cut as it is passing over 25 the die, an edge gage 288 is provided, this gage being mounted upon an arc-shaped slide 290 arranged to slide in an arc-shaped guideway in a gage support 292 adjustably mounted upon a bracket 294 at the front of 30 the machine frame, the support being confined upon said bracket by bolts 296 passing through slotted openings in said support. A spring 300 maintains the slide 290 normally in its operative relation to the die and permits the slide to move downwardly during 35 the cutting operation, the shape of the slide providing for the proper movement of the gage over the inclined outer face of the die.

The lifts or other blanks cut from the material, as hereinabove pointed out, are discharged downwardly through the die, through an opening 302 in the die carrier and through a corresponding opening in the machine frame into a sifting chute 26 which 40 sifts out the imperfect lifts from the perfect lifts. To provide for this sifting operation the chute is pivotally mounted at its front end upon a rod 304 confined in bosses 306 and 308 upon the brackets 284 and 286, and 45 at its rear end is supported by a frame 310 connected to a reciprocating rod 312 by a spring 314, said rod being reciprocated by a wrist pin 316 (Fig. 14) adjustably confined in the slot 318 extending along the diameter 50 of the shaft 10 at the rear end of said shaft, the slot being formed in a disk 320 confined upon the hub of the pulley or fly wheel 322. By adjusting the wrist pin 316 along the slot 318 the amount of shaking action given to 55 the sifting chute 26 can be varied to meet the requirements of the work. A loose pulley 324 upon the shaft 10 receives the belt by which the machine is driven when it is desired to stop the machine, and this belt 60 65 may be shifted to the pulley 322 connected to

the shaft 10 by any suitable belt shifting mechanism. The waste from the cutting operation is received in a chute 326 and discharged into any suitable receptacle.

The illustrated cutting block 20 is preferably made of metal, a suitable metal for this purpose being brass, and the cutting edge of the die is preferably received in a groove 330 in this block formed by the die itself, the block being preferably so adjusted that in its downward movement it stops when the cutting edge of the die is a very short distance from the bottom of this groove. To provide for the accurate vertical adjustment of the block, the plunger 16 which carries the block is constructed as shown in Fig. 10 of the drawings. The plunger 16 is preferably hollow upon its inside, except for a cross partition 332 which separates the upper portion from the lower portion, and through the center of this partition 332 extends the stem 334 of a swivel block having ears 336 between which is pivoted at 338 the pitman 14. The stem 334 of the swivel is confined against vertical movement in the partition 332 by a screw 340 screwed into the lower end of said stem and having a head which bears against a washer 342 on the lower side of said partition. The lower part of the plunger 16 is threaded to receive the threaded stem 344 of the block support 18 and is split at 346 so that said block support may be clamped in its different positions of adjustment. To effect this clamping action a split ring 348 surrounds the split portion of the plunger 16, and extending from this ring adjacent to the opening through its circumference are two wings or lugs 350 connected by a bolt 352 by which the ring may be contracted to cause it to force the split portion of the plunger 16 into clamping relation to the stem 344 of the block support 18. The wings 350 of the split ring 348 also have another function in that they embrace the guide rod 32 to prevent the turning of the plunger 16 relatively to the block support 18. When it is desired to effect a vertical adjustment of the block support 18, the bolt 352 is turned in a direction to loosen the ring 348 upon the plunger 16, a flange 351 upon the plunger preventing the ring from dropping off, and the plunger is then turned in a direction to cause it to screw up or down upon the stem 344.

In practice the groove 330 in the cutting block is preferably formed in the machine in which the die and block are to be used. This formation of the groove may be effected in the following manner: The die having been located in the machine with reference to certain fixed points hereinafter to be referred to, and the block having been located in its support with reference to certain other fixed points hereinafter to be referred to, the sup-

port 18 is adjusted upon the plunger 16 so that when the plunger descends the cutting edge of the die 22 will cut a short distance into the block 20. The support is then adjusted so that a further cut will be made into the block, and this operation is repeated several times until a groove of the desired depth is obtained, after which the block carrier is adjusted so that in the normal operation 10 of the machine the cutting edge of the die will not come quite to the bottom of the groove. By the formation of a groove in this manner there is obtained in this machine substantially a shearing action upon the stock, and the cutting up of the surface 15 of the block, incident to cutting operations in ordinary machines, is avoided.

To provide for the accurate location of the groove in the block 20 and of the die 22 in the machine so that interchangeable dies 20 and co-operating cutting blocks may be provided whereby different sizes and shapes of lifts may be cut, the cutting block 20 is carried upon a dove-tailed slide 354 which is received in a corresponding guideway in the block carrier 18, a gib 356 being located upon one side of said guideway and being 25 pressed into engagement with the slide 354 by means of set screws 357 to insure the location of the slide with its side pressed 30 against the other side of said guideway, the last-mentioned side of said guideway being always in a definite location in the machine. The block carrier slide is thus located in one 35 dimension in the plane of the cutting surface. Its location in the other dimension is effected by means of a locking pin 358 spring 40 pressed by a spring 360 normally toward locking engagement in a socket in the block slide, a hand piece 364 being provided by which the pin may be lifted out of the socket when it is desired to remove the block.

The die 22 is mounted in a die carrier 24, which is shown particularly in Figs. 1, 10, 45 15 and 16, this carrier being substantially circular in outline and being provided with a concentric circular shoulder 366 by which it is located in a circular opening 368 in the machine frame. Upon its upper surface 50 adjacent to the opening 302 the die support or carrier 24 is provided with an abutment 370 (Fig. 16) against which the breast end of the die is forced by means of a slideable clamp member 372 confined upon the upper 55 surface by bolts 374 passing through slots 376 in said clamp member. The slots 376 and bolts 374 serve to guide the clamp member 372 as it is forced toward the abutment 370 by a clamp operating screw 378 60 threaded through the head 380 of a screw 382. A pin 383 upon the machine frame enters one of the holes 384 in the die carrier 24 and serves to determine the angular position of the die carrier 24 in the opening 65 368. The die carrier 24 is provided with

three beveled clamping surfaces 385 adapted to be engaged by the correspondingly beveled upper end of a clamping yoke 387 which is held in clamping position by a square-headed screw 386.

70

In Fig. 15 of the drawings is shown a die having an ordinary straight breast, and when a die of this outline is to be employed it is preferably placed in the machine with the straight breast edge toward the front 75 whereby it substantially coincides with one of the straight sides of the strip from which the blanks are to be cut. In the illustrated machine is shown a straight-breasted die having this edge placed toward the front, 80 and the corner 388 of the die always has the same location in the machine. This location is insured by a pin 390 which passes through one of two openings 392, 394 in the abutment 370 and into an opening in 85 the breast end of the die.

When a die of the shape shown in Fig. 16 is to be employed, that is, a die having a curved breast edge, the die is preferably so located that the curved breast edge is in 90 the line of feed, whereby the convex rear edge of the die may enter into the convex end left upon the stock from the preceding die cutting operation, or, if the die be turned around, the concave breast end of 95 the die may embrace the concavity left from the preceding cutting operation, thus effecting a substantial saving in stock. In the illustrated machine this die is preferably located with the breast edge presented to 100 the direction of feed, the die carrier 24 being turned through an angle of 90°, and the hole 394 being used to locate the corner 396 of this die, which is the point upon this die that has the fixed location in the machine. 105

When dies of different sizes are used it is necessary to change the amount of feed movement imparted to the stock feeding mechanism, and as hereinabove pointed out 110 this is done by turning the screw 130 to move the block 124 in and out along the radius of the gear 92, the scale 134 being so graduated that, when a die of a certain size is placed in the machine, the machine 115 may be set to feed the stock the proper distance by simply turning the screw 130 until the indicator 132 points to the proper indication on the scale 134. Inasmuch as the feeding mechanism is at one side of the die 120 so that the leading end of the stock is not at the edge of the die when the feeding movement begins, it is necessary to provide for feeding the leading end to the edge of the die before the measured feed movement 125 is imparted to the stock which feeds only sufficient stock for a single lift. As hereinabove pointed out, this initial feed of the stock is effected by permitting the stock to enter the feeding mechanism only when 130

such part of the feed movement of this mechanism remains as is sufficient to bring the leading end of the stock to the edge of the die, the stock being prevented from 5 entering the feeding mechanism by the gate 138, against the shoulder 140 of which the leading end of the stock is pressed until the gate is raised after the feed rolls 36 and 38 have started their feeding movement. 10 When the amount of feeding movement of the feed rolls 36 and 38 is changed by the adjusting means hereinabove described it is necessary also to change the time of the lifting of the gate 138 in order to insure 15 the movement of the leading end of the stock only to the edge of the die, and this is done by adjusting the cam 156 about the axis of the shaft 10. To facilitate this adjustment a scale 398 is provided upon 20 the hub of this cam which co-operates with an indicator 400, this scale being provided with graduations corresponding to those upon the scale 134, whereby, by simply setting the cam 156 so that the pointer 400 25 points to the same indication upon the scale 398, the cam 156 will be in proper position to lift the gate at the proper time with this adjustment of the feeding mechanism. In making these adjustments of the 30 machine the shaft 10 is turned into such position that the index mark 402 on the front of the eccentric 12 registers with the index mark 404 on the eccentric sleeve.

The operation of the machine as a whole 35 will now be described. The strip or sheet of material to be cut is placed upon the table 172 with its edge against the edge guide 222, the guide 272 being removed if the machine is to operate upon sheets, in 40 which case a part of the sheet is supported by the table 282. The end of the sheet is then moved toward the feed rolls 36 and 38, and if the feed rolls have not arrived at that part of their feed movement at which 45 the beginning of the feeding of the material should take place, the end of the strip or sheet will come against the shoulder 140 upon the gate 138.

It will be noted that an important feature 50 of this invention is the construction of the gate and the location of the shoulder, by means of a slot in the upper feed roll through which the gate extends, so that this shoulder is approximately at the point where 55 the feed rolls grip the stock when the gate is lifted. Thus the operator, by pressing the end of the strip or sheet against the gate, imparts to the sheet or strip a tendency to move the very slight distance which is necessary 60 to bring it into the field of operation of the feed rolls when the gate is lifted. This permits the machine to be operated at a higher speed than prior constructions without danger of variable operation owing to 65 the failure of the operator to move the strip

or sheet quickly enough into the field of operation of the feed rolls after the gate is lifted to obtain the full feeding effect from the remainder of the feed movement of the feed rolls. As hereinabove pointed out, the 70 gate is lifted at such a time in the movement of the feed rolls that during the succeeding full feed movement the leading end of the stock will be fed to the farther edge of the die, overlapping this edge only sufficiently to insure a full blank, but not far enough to cause any substantial waste of material.

It will be seen that after the gate has been lifted to permit the leading end of the stock 80 to enter the feeding mechanism, upon its next descent it will press upon the upper surface of the stock and its extension 142 will serve to guide and control the stock as it is fed to the cutting mechanism, and that 85 in this guiding and controlling operation it co-operates with the spring member 166. After the first blank has been cut, each succeeding feeding operation of the feed rolls 90 36 and 38 feeds the stock far enough to provide material for a complete blank without waste. This operation will be repeated until the end of the material has passed out of the field of operation of the feed rolls.

Inasmuch as it is not possible to locate the 95 co-operating feeding surfaces of the feed rolls immediately adjacent to the cutting edge of the die, and thus it might happen that a piece of material large enough to make a complete blank would be left with its leading 100 edge only part way across the die, provision has been made for moving this last piece of material so that the last end of the material will be moved into close proximity to the nearer edge of the die, thus insuring the 105 cutting of a complete blank from this last piece, provided the last piece is large enough to form a complete blank. This means as hereinbefore described, comprises the fingers 110 182 which are normally pressed down into the slots in the lower feed roll 38 while the strip or sheet is being fed through them by the feed rolls, these fingers being oscillated only after the feeding movement of the feed rolls has ended, whereby they can 115 spring into position behind the end of the strip or sheet and push this last piece into position in the cutting mechanism after the feed rolls have ceased to act upon this piece. If, as above pointed out, the machine is 120 operating upon a sheet of material, during each feeding operation a portion of the sheet of substantially the width of the blank to be cut will be severed from the main part of the sheet by the action of the co- 125 operating disk cutters 274 and 276.

Having fully described my invention, what I claim as new and desire to secure by Letters Patent of the United States is:

1. In a machine of the class described, cut,

ting means, means located at one side of said cutting means for feeding material into position to be cut by said cutting means, and means for engaging the end of the material as it leaves said feeding means and pushing it toward said cutting means.

2. In a machine of the class described, cutting means, means spaced from said cutting means for feeding measured lengths of material into position to be operated upon by said cutting means, and auxiliary means, operating upon said material after it has ceased to be operated upon by the feeding means, for moving the portion of the material between said feeding means and said cutting means into position to be operated upon by said cutting means.

3. In a machine of the class described, cutting means, feeding means at one side of said cutting means operating to feed measured lengths of material into position to be cut, and means operating on said material after it leaves the feeding means to insure the movement into position for the operation thereon of the cutting means of the last piece which comprises said measured length.

4. In a machine of the class described, cutting means, means comprising a feed roll for feeding material into position to be operated upon by said cutting means, and other means for feeding said material, effective for this purpose from the point where said material is operated upon by said feed roll to a point substantially at the point of operation of said cutting means.

5. In a machine of the class described, cutting means, means comprising a feed roll for feeding material into position to be operated upon by said cutting means, and reciprocating material feeding means operating between said cutting means and the point at which said feed roll engages said material.

6. In a machine of the class described, means for cutting blanks from sheet material, means comprising a pair of feed rolls for feeding material to said cutting means, and means arranged to engage the rear end of the sheet as it leaves said feed rolls for completing the movement of said end into position for the operation of said cutting means.

7. In a machine of the class described, means for cutting blanks from sheet material, means comprising feed rolls for feeding measured lengths of material into position to be cut, and a pusher arranged to engage the end of the sheet of material as it leaves said feed rolls and operating after the feeding movement of said feed rolls is completed to move said end of the sheet into close proximity to the cutting means.

8. In a machine of the class described, cutting means, means for feeding material into position to be operated upon by said

cutting means, and auxiliary, normally inoperative feeding means acting upon said material after said first-mentioned feeding means ceases to act thereon to complete the movement into operative position of said material.

9. In a machine for successively cutting a plurality of blanks from a strip or sheet of material, blank cutting means, means for feeding successive portions of said strip or sheet into position to be operated upon by said cutting means, said means operating upon said strip at a point spaced from said cutting means, and other means, normally held in inoperative position by the strip or sheet, for completing the movement of the strip or sheet into position in said cutting means.

10. In a machine of the class described, the combination with cutting means, and means, comprising feed rolls, for feeding the material to be cut to said cutting means, of means arranged to operate between and beyond said feed rolls for moving the material toward said cutting means after it has left said feeding means.

11. In a machine of the class described, the combination with cutting means, and means comprising feed rolls for feeding material into position to be cut by the cutting means, of means, arranged to operate after said feeding means ceases to operate on the material, to move said material through the space between the cutting means and the point at which the feeding means ceases to operate on said material.

12. In a machine of the class described, the combination with cutting means, and feeding means comprising a feed roll located at one side of the cutting means, of a finger arranged to engage the rear edge of the material, and means for causing said finger to move the material through the space between the point at which it leaves the feed roll and the cutting means.

13. In a machine of the class described, cutting means comprising a die, means for feeding measured lengths of material into position to be cut by the die, said feeding means being spaced from said die, and means for moving the last end of said material into close proximity to the nearer edge of the die.

14. In a machine of the class described, feeding mechanism comprising feed rolls arranged to engage opposite faces of the material to be fed, and a pushing finger, yieldingly pressed normally toward operative position, one of said rolls being provided with a groove in which said finger is received while the material is being fed by said feed rolls.

15. In a machine of the class described, cutting means, means comprising a feed roll for feeding material to be cut to said cutting means, and a pair of pushing fingers ar-

- ranged to engage the rear edge of the material and to move it through the space between the point at which it leaves said feed roll and said cutting means.
- 5 16. In a machine of the class described, feeding means comprising a pair of feed rolls arranged to engage the material upon its opposite faces, and a pushing finger operating in grooves in said feed rolls to engage 10 the end of the material.
17. In a machine of the class described, cutting means, means comprising a feed roll for feeding material to be cut to said cutting means, and means supported upon the side 15 of said feed roll remote from the cutting means and movable past said feed roll to effect a feeding operation between the point at which said feed roll acts upon the material and said cutting means.
- 20 18. In a machine of the class described, cutting means, means comprising a feed roll for feeding material to be cut to said cutting means, and means, normally held in inoperative position by the material, for moving 25 the last end of the material into position to be cut.
19. In a machine of the class described, cutting means, means comprising a feed roll for feeding material to be cut to said cutting 30 means, and means, normally held in inoperative position by the material; for moving the last end of the material into position to be cut, said feed roll being provided with a groove into which said means enters as it moves into operative position.
20. In a machine of the class described, feeding mechanism comprising coöperating feed rolls, and a pushing finger arranged to engage the end of the material as it is leaving 40 said feed rolls, one of said rolls having a groove into which said finger may be pressed as the material passes through said rolls.
21. In a machine of the class described, 45 feeding mechanism comprising a feed roll, and a stop for controlling the presentation of the material to be fed to said feed roll, said stop presenting an acting face in substantially perpendicular relation to the path 50 of movement of the material and immediately adjacent to the point at which the feeding surface of said roll engages the material, the stop being movable out of said location while the material is held against it 55 in order to permit the presentation of the material to the feeding mechanism.
22. In a machine of the class described, 60 feeding mechanism comprising a feed roll, a stop for controlling the presentation of the material to be fed to said feed roll and against which the end of said material may be thrust, said stop having its acting face substantially perpendicular to the plane of the material immediately adjacent to the 65 point at which the feeding surface of said

roll engages the material to feed it, and means for automatically moving said stop out of the path of the feeding movement of said material.

23. In a machine of the class described, 70 feeding mechanism comprising a feed roll, means for intermittently turning said feed roll, a stop for controlling the presentation of the material to be fed to said feed roll and against which the material to be fed is 75 thrust, said stop having its acting face substantially perpendicular to the plane of the material immediately adjacent to the point at which the feeding surface of said roll engages the material to feed it, and means for 80 automatically moving said stop out of the way of the material at a predetermined time in the operation of said feed roll.

24. In a machine of the class described, 85 feeding mechanism comprising coöperating feed rolls, and a gate presenting a stop surface against which the material to be fed is thrust and another surface for guiding the material after it enters the feed rolls, said stop surface upon said gate being located 90 immediately adjacent to the point at which the feeding surfaces of said rolls coöperate to engage and feed the stock and said gate being constructed and arranged to be lifted to permit the end of the stock to be engaged 95 by said coöperating feeding surfaces.

25. In a machine of the class described, 100 feeding mechanism comprising coöperating feed rolls, one of which is provided with a peripheral slot, and a gate located in said slot, presenting a stock locating shoulder in immediate proximity to the point at which the coöperating feeding surfaces of said rolls engage the stock to be fed and movable in said slot out of the path of said stock, 105 whereby said rolls may be permitted to engage and feed said stock.

26. In a machine of the class described, 110 cutting means, means for feeding measured lengths of material to said cutting means, and means comprising a gate for controlling the time of presentation of the leading end of the material to said feeding means, said gate being provided with another face which serves as a guide for said material after it 115 enters said feeding means.

27. In a machine of the class described, 120 cutting means comprising a die, automatic means for feeding measured lengths of material to be cut to said die constructed to feed the leading end of the material to a point in close proximity to the farther edge of the die, and automatic means for feeding the last end of the material, whatever the length of said material, to a point in close 125 proximity to the nearer edge of the die.

28. In a machine of the class described, 130 the combination with cutting means comprising a die, of means spaced from said die for feeding measured lengths of material to

said die, means controlling the effective operation of said feeding means constructed to cause said feeding means to feed the leading end of the material to a point in close proximity to the farther edge of the die, and means for moving the last end of said material to a point in close proximity to the nearer edge of the die.

29. In a machine of the class described, 10 in combination with cutting mechanism comprising a blank cutting die constructed and arranged to be interchanged with dies of other sizes, means for feeding measured lengths of material to said cutting mechanism adjustable to suit its feeding movement to dies of different sizes, and means for controlling the time of presentation of the material to be cut to said feeding means in such manner as to insure cutting the first 20 blank without waste, said means being also adjustable to suit its timing to the adjustment of the feed mechanism, said adjustments being graduated in die sizes.

30. In a machine of the class described, 25 cutting means, feeding means located at a measured distance to one side of said cutting means, means for operating said feeding means to feed the material to be cut uniform measured distances, means for preventing the leading end of the material to be cut from entering said feeding means until a part of the feed movement corresponding to the difference between said measured distance and the normal feed movement, or a 35 multiple thereof, has taken place, and means for engaging the last end of the material to be fed constructed to move said material between said feeding means and said cutting means.

40 31. In a machine of the class described, cutting means comprising a blank cutting die, means located in advance of and closely adjacent to said cutting means for feeding measured lengths of material into position 45 to be cut, and means for cutting the material into measured widths connected to and operating with said feeding means.

32. In a machine of the class described, 50 cutting means comprising a blank cutting die, intermittently operated means for feeding measured lengths of material to the cutting means, and strip cutting means located in advance of the first-mentioned cutting means and operated by said feeding means.

55 33. In a machine of the class described, dieing-out means, intermittently operated feed rolls located in advance of the dieing-out means and operative for feeding measured lengths of material into position to be 60 cut by the dieing out means, and rotatable strip cutting means located in advance of the dieing-out means and connected to and operated from said feeding means.

34. In a machine of the class described, 65 cutting means comprising a blank cutting

die, means for feeding measured lengths of material to the cutting means, and means connected to and operating in time relation to said feeding means for cutting a straight edge along the material to be fed in advance 70 of the operation of the blank cutting die.

35. In a machine of the class described, cutting means comprising a blank cutting die operating across the path of feed of the material to be cut, feeding means comprising feed rolls, means for operating said rolls to feed measured lengths of material into position to be cut by the blank cutting die, and coöperating cutters at the ends of said feed rolls for cutting the material into measured widths as it is fed to the blank cutting die.

36. In a machine for cutting blanks from sheet material, a blank cutting die, means for feeding measured lengths of material 85 into position to be cut by said blank cutting die, and means associated with said feeding means and operating in time relation thereto for cutting a measured width of material from the sheet to be operated upon as said 90 material is fed to said blank cutting die.

37. In a machine of the class described, cutting means, means for feeding measured lengths of material to said cutting means, stripping means so mounted upon said feeding means that it cuts from the material fed that which lies outside of the field of operation of said cutting means, and means for engaging the end of the strip thus finally severed and moving it farther along the line 100 of feed after it leaves said feeding means.

38. Work feeding mechanism for sheet material comprising feed rolls, shafts upon which said feed rolls are mounted, a toggle connected at its ends to the respective shafts, 105 means operating upon said toggle for yieldingly maintaining said shafts in predetermined relation to each other, and means for varying said predetermined relation.

39. Work feeding mechanism for sheet 110 material comprising feed rolls, means comprising a toggle for moving said rolls toward and away from each other, adjustable means for positively limiting the movement of the toggle in one direction, and means for yieldingly preventing its movement in the other direction.

40. Means for feeding sheet material comprising feed rolls, driving means to which said rolls are independently connected and 120 by which they are turned in unison, and means comprising a toggle for adjusting said rolls toward and away from each other.

41. Mechanism for feeding sheet material comprising feed rolls, driving means for said rolls to which they are independently connected, parallel shafts upon which said rolls are mounted, swinging supports for said shafts, and means comprising a toggle for swinging said supports.

42. Mechanism for feeding sheet material comprising a pair of coöperating feed rolls, driving means for said rolls to which they are independently connected, parallel shafts upon which said rolls are mounted, swinging supports for said shafts at one side of the path of the material fed by said feed rolls, and means comprising a toggle for swinging said supports. 65
- 5 43. Means for feeding sheet material comprising coöperating feed rolls, pinions connected to said feed rolls, and gears for operating said pinions, said feed rolls being adjustable toward and from each other 70 about the axes of said gears. 10
- 15 44. Work feeding mechanism for sheet material comprising coöperating feed rolls, shafts on which said rolls are mounted, swinging supports for said shafts, pinions upon said shafts, and gears for operating 75 said pinions arranged to turn about axes coinciding with the axes about which said supports swing. 20
- 25 45. Means for feeding sheet material comprising feed rolls, pinions connected to said feed rolls, gears for operating said pinions, and means for moving said feed rolls toward and away from each other constructed to move said rolls about the axes of said gears. 80
- 30 46. In a machine of the class described, feeding means comprising feed rolls, means for intermittently turning said feed rolls comprising a roller ratchet mechanism, and connections between said roller ratchet and said feed rolls constructed to slip when the 85 free turning of said feed rolls is prevented. 35
- 40 47. In a machine of the class described, feeding mechanism comprising a feed roll, positively driven means for intermittently turning said feed roll, and connections between said means and said feed roll constructed to slip when the free turning of said feed roll is prevented. 90
- 45 48. In a machine of the class described, cutting mechanism, means for feeding measured lengths of material to said cutting mechanism, positively operated means for operating said feeding means, and connections between said positively operated means 95 and said feeding means constructed to slip when more than a predetermined resistance is offered to the feeding movement of said feeding means. 100
- 50 49. In a machine of the class described, a stationary die, a cutting block movable toward and away from said die, means for feeding measured lengths of material over said die, a stripper located between said feeding means and said die, and means arranged to yield into said stripper during the cutting operation for guiding the leading end of the material over said stripper and die. 105
- 55 50. In a machine of the class described, the combination with cutting means and feed rolls to feed measured lengths of material into position to be operated upon by said cutting means, of means extending between and beyond said feed rolls toward said cutting means for supporting and guiding the material operated upon by said feed rolls. 110
- 55 51. In a machine of the class described, the combination with cutting means and feed rolls constructed and arranged to feed measured lengths of material to said cutting means, of means, extending between and beyond said feed rolls toward said cutting means and arranged to engage the material upon both faces, for guiding and controlling the presentation to the cutting means of the material fed by said feeding means. 115
- 55 52. In a machine of the class described, the combination with cutting means and means, comprising feed rolls, for feeding measured lengths of material to said cutting means, of means extending between and beyond said feed rolls toward said cutting means and arranged to engage the material upon both faces for guiding and controlling the presentation to the cutting means of the material fed by said feeding means, and means arranged to be moved between and beyond said feed rolls for engaging the end of the material fed and moving it through the space between said cutting means and the point where said material leaves said feed rolls. 120
- 55 53. In a machine of the class described, the combination with cutting means, of means for feeding measured lengths of material to said cutting means, means comprising a roller ratchet mechanism for operating said feeding means, said ratchet mechanism comprising a driving member, means for varying the movement of the driving member of said roller ratchet mechanism, and means controlled by the last-mentioned means for indicating the desired variation in said movement. 125
- 55 54. In a machine of the class described, cutting means comprising a die, a die stripper, and a gage, said stripper and gage normally projecting beyond the plane of the cutting edge of the die and being arranged to yield through said plane during the cutting operation, said gage being movable relatively to said stripper during said cutting operation. 130
- 55 55. In a machine of the class described, cutting means comprising a die, and gages upon opposite sides of said die for locating the material to be cut, said gages projecting normally beyond the plane of the cutting edge of the die and being arranged to yield through said plane during the cutting operation and to separate during said yielding movement. 135

56. In a machine of the class described, cutting means comprising a die, a die stripper, gages upon opposite sides of said die for locating the material to be cut, said stripper and said gages projecting normally beyond the plane of the cutting edge of said die and being arranged to yield through said plane during the cutting operation, said gages and said stripper being 10 relatively movable during the yielding movement.
57. In a machine of the class described, cutting means, means for feeding the material to be cut to said cutting means, a gage 15 against which the edge of a sheet of material may be placed as it is presented to said feeding means, means, connected to and operated from said feeding means, for severing a measured width of material from said 20 sheet as it is fed, a gage upon one side of said cutting means in line with said before-mentioned gage, and a gage upon the other side of said cutting means in line with said severing means.
- 25 58. In a blank cutting machine, a die having an outer face which slopes outwardly from the cutting edge, a gage located in close proximity to said cutting edge for locating the material to be cut upon said die, 30 said gage being movable during the cutting operation transversely to the plane of said cutting edge and being guided for movement obliquely to said plane over said sloping outer face.
- 35 59. In a blank cutting machine, a die having outer faces which slope outwardly from the cutting edge, means for feeding material to be cut to said die, means for centering the material over said die comprising 40 gages upon opposite sides of the path of feed of the material in close proximity to the cutting edge of said die, and means for 45 yieldingly maintaining said gages in operative relation to the die constructed to guide said gages obliquely out of said operative relation during the cutting operation.
60. In a machine of the class described, the combination with cutting means comprising a die and a die block, of feeding means comprising feed rolls located at one side of said die, a die stripper located between said feed rolls and said die, and means for pushing the end of the material between the point at which said material leaves said 55 feed rolls and the cutting mechanism, said stripper being provided with a recess in which said pushing means is received.
- 60 61. In a machine of the class described, a cutting block having formed therein a permanent, shallow, die-receiving groove which has the contour of the cutting edge of said die, the material of which said block is formed being sufficiently resistant to the pressure of the block to insure the perman- 65 nency of said groove both in outline and in section.
62. In a machine of the class described, a cutting die, and a metallic cutting block having formed therein a die-receiving groove shaped to fit the cutting edge of said die, and means for effecting a relative cutting movement of said die and said block, constructed to cause the cutting edge of said die to enter said groove.
63. In a machine of the class described, a 70 metal cutting block having formed therein a die receiving groove shaped both in outline and in section to fit the cutting edge of the die with which said block co-operates.
64. In a machine of the class described, the combination with a cutting die and a cutting block having formed therein a permanent die receiving groove shaped in contour and in section to fit the cutting edge of said die, of means for effecting a relative 75 cutting movement of said block and said die, having provision for adjustment whereby the depth of penetration of the cutting edge of said die into said groove may be accurately predetermined.
65. In a machine of the class described, a cutting die and a cutting block, said cutting block being provided with a die receiving groove having the outline of the cutting edge of said die, and means for effecting a relative cutting movement of said block and said die constructed to move said die into 80 said groove but not to the bottom thereof.
66. In a machine of the class described, a cutting die having a cutting edge forming a closed outline, a metal cutting block having a die receiving groove formed by forcing the cutting edge of said die into the material of said block, and means for effecting a relative cutting movement of said 85 block and die constructed to cause said die to enter said groove but to stop short of the bottom thereof.
67. In a machine of the class described, cutting mechanism comprising a die, a metal block having formed therein a die receiving groove corresponding in contour to the contour of the cutting edge of said die, means for effecting a relative cutting movement of said die and said block, said die and block 90 being adjustable relatively to each other, whereby the cutting edge of the die may be caused to enter a predetermined distance into the groove in said cutting block during the cutting operation.
68. In a machine of the class described, cutting means comprising a die, a die stripper, and means for moving material to be cut into close proximity to said die, said die stripper being provided with a recess into 95 which said means enters during its material feeding movement.
69. In a machine of the class described,

cutting means comprising a die, means for feeding material to be cut to said die, a die stripper between said die and said feeding means, and means for moving the last end of the material into close proximity to the nearer edge of the die, said last-mentioned means being inoperative during the normal material feeding operations and said stripper being provided with a recess in which said means is received at such times.

70. In a machine of the class described, cutting means comprising a die, a die stripper, material guiding means, and material feeding means, said stripper being provided with recesses in which said guiding and feeding means are received during the cutting operation.

71. In a machine of the class described, cutting means comprising a die, a die stripper, means for feeding material to said die, comprising a feed roll, and means for moving the last end of the material between the point at which the feed roll operates upon said material and the die, said last-mentioned means being normally inoperative and said roll and said stripper being provided with grooves in which said means is received when inoperative.

72. In a machine of the class described, cutting means, and means comprising feed rolls for feeding material into position to be operated upon by said cutting means, and means extending between and beyond said feed rolls for supporting and guiding the material fed, said rolls being provided with recesses in which said supporting and guiding means are received.

73. In a machine of the class described, the combination with cutting means, and means comprising a feed roll for feeding material to be cut to said cutting means, of means, comprising a spring member extending past the point at which said roll engages the material, for guiding and supporting the material fed, said roll being provided with a groove in which said member is received.

74. In a machine of the class described, the combination with cutting means, and means comprising feed rolls for feeding material to be cut to said cutting means, of means, extending between and beyond said feed rolls toward said cutting means, for supporting and guiding the material fed, and means for yieldingly pressing said supporting and guiding means into engagement with the opposite faces of said material.

75. In a machine of the class described, cutting means comprising a die, means comprising a feed roll for feeding material to be cut to said die, a die stripper between said die and said feeding means, and means, comprising a spring member supported upon the side of said feed roll remote from said

die and extending past said roll into proximity to said die, for supporting and guiding the material fed over said stripper, said stripper being provided with a recess in which said member is received during the cutting operation.

76. In a machine of the class described, feeding mechanism comprising a feed roll, a stop for controlling the presentation of the material to be fed to said feed roll and against which the end of said material may be thrust, said stop being located immediately adjacent to the point at which the feeding surface of said roll engages the material to feed it, and being movable out of said location while the material is held against it in order to permit the presentation of the material to the feeding mechanism, and a guard in front of said feed roll extending into close proximity to the path of movement of the material and constructed to guide the material to said stop.

77. That improvement in the art of forming cutting blocks, which consists in placing in a cutting machine constructed to effect a relative cutting movement thereof a die and a block having a plane surface of a material somewhat softer than the die but harder than the material to be cut, then effecting a relative movement of said block and said die such that the cutting edge of said die is forced into the surface of said block.

78. That improvement in the art of preparing a cutting block for use in a machine in which the block and a coöperating die are moved relatively into and out of cutting relation to each other, which consists in locating in such a machine a die and a block having a die receiving face of material somewhat softer than the die but harder than the material to be cut, effecting a relative movement of approach of said die and block such that the cutting edge of said die is forced into the surface of said block, adjusting the limit of approach and repeating this operation until a die receiving groove of the desired depth has been obtained, and then adjusting the limit of approach so that said die will enter said groove but will not strike the bottom thereof.

79. In a machine of the class described, the combination with cutting means and means comprising a feed roll for feeding material to said cutting means, of a gate for controlling the time of presentation of the leading end of the material to said roll, said gate having an extension projecting through a slot in the roll in the direction of feed to guide the material during its feed movement.

80. In a machine of the class described, a stationary die, a cutting block movable toward and from the die, means for feeding

material between the cutting block and the die, a stripper positioned between said feeding means and the die and movable in directions transverse to the plane of the material, and a member arranged to engage in

5 a slot in said stripper for guiding the material between the feeding means and the die.

81. In a machine of the class described, a stationary die, a cutting block movable toward and from the die, feed rolls for feeding material between the cutting block and the die, a stripper positioned between said rolls and the die and movable in directions transverse to the plane of the material, and

10 a member extending through a slot in one of the feed rolls and movable with said stripper for guiding the material between the feed rolls and the die.

82. In a machine of the class described, the combination with means for cutting blanks from sheet material comprising a die, of a feed roll, means for imparting intermittent movements to said roll to feed the material to the blank cutting means, and 25 means, operative in advance of the die, for slitting the material in parallel relation to the direction of feed during its feed movement, said slitting means comprising a rotary cutter mounted to turn with the feed 30 roll.

83. In a machine of the class described, the combination with cutting means, of means comprising a feed roll for feeding material to said cutting means, an edge 35 guide for the material and means for slitting the material in parallel relation to the direction of feed during its feed movement, said slitting means comprising a rotary cutter mounted to turn with said roll and adjustable in the line of the axis of the roll and toward or from said edge guide for slitting the material at different distances from its edge.

84. In a machine of the class described, the combination with cutting means, of means comprising a pair of feed rolls for feeding material to said cutting means, an edge guide for the material, and a pair of 45 rotary disk cutters mounted coaxially with said feed rolls for slitting the material in parallel relation to said edge guide, said

cutters being adjustable in the line of the axes of the rolls for slitting the material at different distances from said guide.

85. In a machine of the class described, the combination with cutting means, of means for feeding material to said cutting means comprising a feed member and mechanism for operating said member, said mechanism including a gear wheel arranged 55 for movement against yielding resistance in case the normal movement of said member is prevented.

86. In a machine of the class described, the combination with cutting means, of means for feeding material to said cutting means comprising a feed roll and mechanism for imparting intermittent turning movements to said roll, said mechanism including a gear wheel and its shaft arranged 60 for yielding movement in the event of abnormal resistance to the turning movement of the roll.

87. In a machine of the class described, a blank cutting die beveled on its outer surface to form a cutting edge, gages at opposite sides of said die for locating the material to be cut by the die, said gages being yieldably movable through the plane of the cutting edge of the die during the cutting 75 operation, and means independent of the die for causing said gages to separate during said yielding movement.

88. In a machine of the class described, a blank cutting die beveled on its outer surface to form a cutting edge, and a gage at one side of the die for locating an edge of the material close to the edge of the die, said gage being curved in transverse relation to the plane of the cutting edge of the die and movable transversely of said plane about the axis of said curve in the cutting 80 operation to cause the gage to recede laterally from the die during its movement.

In testimony whereof I have signed my 95 name to this specification in the presence of two subscribing witnesses.

WILLIAM C. BAXTER.
